PAPER SOCKER

William V. Henry, Candler, N. C., assignor to American Enka Corporation, Enka, N. C., a corporation of Delaware

Application May 22, 1953, Serial No. 356,614

6 Claims. (Cl. 53—13)

This invention relates to the application of a covering material to a hollow package and more particularly to a method and apparatus for mutually manipulating a paper-like covering material and package during a wrapping operation.

The present invention is particularly useful for the application of a protective covering member having a restricted flexibility of the nature of a paper sleeve to a hollow package of artificial filaments, such as a cake of rayon obtained by collection in a spinning pot.

Although various devices have been developed to mechanically apply flexible knitted or woven sleeves to rayon cakes (see Patents Nos. 2,418,657 and 2,436,481), it has not been possible to do the same with paper sleeves having a limited flexibility. The devices of the patents could not be adapted for such use as it was determined that in manipulating the paper sleeves in this manner they were torn and otherwise rendered unsuitable.

Therefore, normally the procedure of covering the package with paper, hereinafter designated as socking, was performed by hand. This procedure of manually socking the cakes not only consumed considerable time but often resulted in irregular filaments due to the prolonged handling.

This invention therefore provides for the socking of cakes with paper in less time than was heretofore required while also reducing one factor tending to cause irregularity in filaments.

It is an object of this invention to provide a simplified form of apparatus for the application of a protective covering material having a restricted flexibility to a hollow package of artificial filaments such as a freshly formed cake of rayon.

Other objects and advantages of this invention will become apparent from the following detailed description when considered in conjunction with the accompanying drawings, wherein:

Figure 1 shows a front view in elevation partly in section of the apparatus of this invention when in a fully expanded position, the package being removed for purposes of better illustration;

Figure 2 is a fragmentary view of a portion of the apparatus of Figure 1 showing the relationship of parts when in the normal position of repose;

Figure 3 is a plan view of the apparatus of Figure 1;

Figure 4 is a fragmentary side elevation view at right angles to the view point of the apparatus of Figure 1; and

Figures 5, 6 and 7 are detailed sectional views showing the cycle of operation of socking a hollow package.

Referring now to the drawings and more particularly to Figures 1 to 4, the socking apparatus is supported on a frame generally indicated at 10 which includes four legs 11, the upper ends of which are fixed to a ring 12. Connected to the frame by being secured to braces are cross-bars 13 and 14. Cross-bars 13 and 14 serve as support members for the upper and lower ends, respectively, of shaft 15 and maintain shaft 15 in a vertical position. Cross-bar 13 has a hole therethrough forming a bearing

2

therein through which shaft 15 may pass when the apparatus is being assembled or disassembled. When the apparatus is assembled, however, the upper end of shaft 15 rests within the bearing. Cross-bar 14, against which shaft 15 rests, has a collar 16 attached thereto within which the lower end of shaft 15 is removably mounted. Surrounding the lower portion of shaft 15 is a slidable sleeve 17 which normally rests on collar 16 when the apparatus is in a position of repose as shown in Figure 2.

Extending between two of the legs 11 with each of its ends secured to one of the legs is a shaft 18 about which is pivoted a pedal lever 19. Fixed to one end of the pedal lever is a pedal 20. The other end of the pedal lever is forked at 21 to fit around collar 16 when the apparatus is in a position of repose as shown in Figure 2 and raise the slidable sleeve 17 upwardly along shaft 15 when the foot pedal is depressed as shown in Figure 1. Above the slidable sleeve 17 and fixed to the shaft 15 by means of a set screw is a collar 22 which restricts the upward movement of the sleeve 17 along the shaft 15.

Surrounding the upper portion of the shaft 15 is another slidable sleeve 23. Also surrounding the shaft 15 and fixed thereto on each side of the slidable sleeve 23 are collars 24 and 25. Collars 24 and 25 restrict the longitudinal movement of sleeve 23 along the shaft 15. The collars 16, 22, 24 and 25 are so positioned on shaft 15 as to allow for less longitudinal movement of sleeve 23 than sleeve 17. The reason for this lesser movement will be discussed more fully hereinafter. Surrounding shaft 15 and in contact with sleeve 23 and collar 24 is interposed spring 26. Spring 26 is compressed by the combined weights of the slidable sleeves 17 and 23 and their attaching elements when the apparatus is in a position of repose as shown in Figure 2, but upon the depression of the foot pedal which releases the spring 26 of substantially all weight except that of the slidable sleeve 23, forces the slidable sleeve 23 upwardly along the shaft 15 until the upward movement of the sleeve 23 is stopped by its contacting the collar 25.

Extending downwardly from the sleeve 17 and having one end of each fixed thereto are a plurality of radial rods 27. The other ends of the rods are forked at 28 and pivotally connected to the ends of levers 29. Extending substantially downward from slidable sleeve 23 when the apparatus is in a position of repose and having one end of each pivotally connected thereto are a plurality of radial links 30. Similarly, the other end of each of the radial links 30 is forked and pivotally connected to an intermediate portion of one end of the levers 29.

Referring now to ring 12 there are two platforms 31 mounted thereon and located diametrically across from each other. Mounted on each of the platforms 31 is a support 32 pivotally mounted at an intermediate portion of the half ring bars 33. Secured to one end of each of the bars 33 is a half ring 34 upon which the package is initially supported. The other end of each of the bars 33 pivotally mounts one end of a slotted bifurcated lever 35. The slotted and bifurcated portions of levers 35 fit over two of the levers 29. These two levers 29 carry pins 36 therethrough which ride within the slots so that upon the vertical movement of lever 29 the pins 36 will ride within the slots to their ends and then force levers 35 upwardly to pivot the half rings 34 to an open position.

Also mounted on each of the platforms 31 is a support 37 slightly offset from support 32 as best shown in Figure 3 which pivotally mounts a clamp 38. Extending at right angles to the half ring bar 33 and fixed thereto intermediate the half ring 34 and its pivot point is a lug 39 which comes into contact with the clamp 38 to force it outwardly after the half rings 34 have been forced outwardly through a substantial arc.

Referring now more particularly to lever 29 the upper ends of which carry vertical fingers 40 which move from a position beneath the filament package to a position surrounding the package when the foot pedal is depressed. The upper ends of some of the levers 29 also carry ears 41 thereon upon which the completely socked package may rest after the fingers 40 have been completely expanded.

With the parts constructed and arranged as hereinbefore described the operations as shown by Figures 5-7 briefly stated is as follows:

With the half rings 34 in the closed position such as that shown in Figure 5 a package of artificial filaments is placed upon the half rings 34. A paper sleeve 42 of a length several times the height of the cake is then placed over the outside of the package and the clamp 38 is closed to hold the paper sleeve against the package. The paper sleeve extending above the package is then collapsed and passed down through the center of the package until it extends below the package. The portion of the paper sleeve extending below the package is then flared out and placed over the fingers 40 as shown by dashed lines in Figure 5. While supporting the cake with both hands the operator presses the foot pedal. The depressing of the foot pedal raises the forked end 21 of pedal lever 19 and thereby the sleeve 17. When the sleeve 17 moves upwardly along the shaft 15 and with it the lever 29 they no longer act to compress the spring 26. With the pressure released on the spring 26 the spring 26 expands to force the sleeve 23 upwardly along the shaft until it reaches the collar 25 whereupon its upward movement is stopped. The sleeve 23 because of the difference in stroke length of sleeves 23 and 17 reaches the collar 25 before the sleeve 17 reaches the collar 22. Inasmuch as the sleeve 17 is still continuing to move in an upward direction the links 39 pivoting on the sleeve 23 move to a more horizontal position and thus increase the diameter of the horizontal area enclosed by the fingers 40.

Simultaneously with the upward movement of the lever 29 the pins 36 slide along the slots until they reach the end of the slots whereupon a further upward movement of levers 29 forces the half rings 34 and thus the clamp 38 to spread apart thus removing all support from the package. The pivoting of the half rings 34 to their open position occurs upon the fingers 40 reaching their expanded position. Fingers 40 now fully expanded horizontally continue to move in an upward direction thus forcing the paper sleeve to cover the outside of the cake while the package now unsupported moves downwardly between the fingers 40 until it comes to rest on the ears 41 of the levers 29. The socking of the package has then been completed and may be removed from the apparatus for further treatment or storage.

What is claimed is:

1. Apparatus for manipulating a hollow yarn package during application of a paper sleeve thereto which comprises supporting means movable to and from a position in supporting relationship to one annular end wall of the package, clamping means movable to and from a position engaging the side wall of said package to hold the sleeve against axial movement, means movable to and from a position to spread the sleeve over said annular end wall, said spreading means comprising a plurality of levers, means responsive to predetermined upward movement of said levers to spread the same radially and to move said supporting means from supporting position and means responsive to movement of said supporting means away from supporting position to move said clamping means away from clamping position.

2. An apparatus for applying a tubular protective covering member to a hollow yarn package which comprises elongated spreading elements for spreading the covering over the lower end of the yarn package, a rod connected to the lower end of each element, a link connected at one end to an intermediate point on each element, a rod lifting means, means to lift the other end of said links, said rod lifting means having a longer stroke than said link end lifting means, pivotally mounted yarn package supporting means, means interconnecting said supporting means and two of said elements and means to initiate concurrent movement of said rod lifting means and link end lifting means.

3. The apparatus of claim 2 which includes means to maintain said link end lifting means above said rod lifting means in a vertical spaced relationship.

4. An apparatus for applying a paper cover to a hollow yarn package which comprises elongated spreading elements for spreading the cover over the lower end of the yarn package, a rod connected to the lower end of each element, a link connected at one end to an intermediate point on each element, a vertical shaft, a first sleeve slidably mounted on said shaft, said first sleeve being secured to said rods, a first pair of fixed collars mounted on said shaft and positioned above and below said first sleeve to allow for restricted movement of said first sleeve along said shaft, a second sleeve slidably mounted on said shaft above said first sleeve and collars, a second pair of fixed collars mounted on said shaft and positioned above and below said second sleeve to allow for restricted movement of said second sleeve along said shaft, a spring encircling said shaft intermediate said second sleeve and lower collar of said second pair to move said second sleeve upwardly along said shaft, a pedal lever operatively connected to said first sleeve to lift said first sleeve pivotally mounted yarn package supporting means, means interconnecting said supporting means and two of said elements and means to initiate concurrent movement of said rod lifting means and link end lifting means.

5. The method of covering a hollow yarn package with a tubular covering of limited flexibility and long enough to cover all surfaces of the package that comprises initially surrounding the outer surface of the package while in a vertical position with one end of the tubular covering, drawing the remainder of the tubular covering across the upper end and down through the interior of said package, thereafter spreading the tubular covering over the lower end of said package and dropping the package while spreading the remaining covering over the outer surface of the package.

6. The method of covering a hollow yarn package with a tubular covering having a limited flexibility and long enough to cover all surfaces of the package that comprises initially surrounding the outer surface of a supported package with one end of the tubular covering, drawing the remainder of the tubular covering across an unsupported end and through the interior of said package, thereafter spreading the tubular covering over the other end of said package following removal of said support and dropping the package while spreading the remaining covering as a second layer over the outer surface of the package.
